DENTAL MATRIX RETAINER

James D. Morrison, Medicine Hat, Alberta,
Canada

Application August 6, 1942, Serial No. 453,891

5 Claims. (Cl. 32—63)

This invention relates to a dental matrix holder and it consists in the constructions, arrangements and combinations herein described and claimed.

In the dental art, a matrix is known as consisting of a combined band and retainer, the band being employed to horizontally surround the walls of a tooth, while the matrix retainer is manipulated to effect a proper tension upon the hand while a cavity is being filled.

In prior constructions of matrix retainers it has been difficult to effect a proper retention of the matrix band upon a tooth where considerable decay has occurred, particularly around the vertical walls of a tooth, since actual contact surface between the tooth and band has been reduced to a large extent.

It is therefore an object of the invention to provide a novel construction of matrix and band in which a uniform tension upon the band is effected firmly holding the band snugly around all surfaces of a tooth.

It is also an object of the invention to afford a matrix holder in which a simplified construction is provided for holding the band upon a pair of opposite movable blocks, the holding means being readily releasable from the band so that the latter may be removed laterally from a tooth, as will be required in many cases, or where necessary, the band may be removed in a direction longitudinally of the tooth.

More specifically, it is an object of the invention to provide a novel construction of matrix holder in which a rigid block embodies a guide channel cooperable with a movable block constructed to traverse the channel upon actuation of an operating worm shaft, the interengagement between the channel and movable block being such that the movable block will partake of a smooth motion, free of any binding tendency upon the worm shaft; and to provide each of the blocks with a clevis device for attachment of respective ends of a matrix band.

Additional objects, advantages and features of invention will be apparent from the following description considered in conjunction with the accompanying drawing, wherein

Figure 1 is a top plan view of the matrix retainer and band applied to a tooth.

Figure 2 is an edge view of the matrix retainer.

Figure 3 is a longitudinal sectional view thereof.

Figure 4 is an enlarged cross section through the matrix retainer.

Figure 5 is an end view thereof.

Figure 6 is a perspective view of the retainer.

Figure 7 is a perspective view of the matrix band in position to receive the retainer.

Figure 8 is an enlarged detail illustrating the operative position of the band securing means.

There is illustrated a matrix holder generally indicated by the reference character 10 which consists of an elongated channel body member 11 having parallel side walls 12 and a smooth rounded base wall 13, so that angular portions are avoided which might be uncomfortable to a patient when in use. The upper ends of the walls 12 are inwardly turned in the direction of the longitudinal axis of the body forming opposed flanges 14 each of which stop a substantial distance outwardly from said axis for a purpose as will presently appear. Integrally formed with the body there is a block member 15 of a height projecting beyond the upper edges of the flanges 14. Formed in the block 15 there is a threaded opening 16 extended in a plane incident with the channel of the body member, and spaced so that the flanges 14 extend approximately in the medial center of the opening 16. Within the channel of the body member 10 there is a movable block 17, the base portion of which is shaped to correspond to the bottom wall 12 for snug yet slidable engagement therein. In order to accommodate the opposed flanges 14 of the channel member, the block is formed with a slot 18 upon each side extending the full length of the block, adapted to receive respective flanges therein. By this construction, it will be apparent that the block 17 may partake of sliding movement along the channel without liability of vertical or lateral movement. The block 17 is also formed with a threaded opening 19 aligned with the opening 16 and through these openings there is a worm shaft 20 of a length greater than that of the body 11, the end 21 of which is provided with a squared end 22 for reception of a manipulating handle 23 for rotating the shaft 20 to effect simultaneous movement of the body member and the movable block.

The shaft 20 is provided with oppositely threaded portions 24 and 25 and preferably the portion 24 is left-handed and the latter right-handed so that a rotation of the shaft 20 in a clockwise direction will tend to separate the blocks and effect the tightening of a band engaged with respective blocks.

The blocks 15 and 17 are each provided with respective pins 26 secured in the upper faces thereof, the pins being inclined from the vertical axis of the blocks in opposite directions. A loop device 27 is swingably mounted upon each block

cooperable with respective pins for securing the ends of the matrix band as will be described hereinafter. In the present instance, the loops are formed from a suitable gauge of steel wire bent to form a bight portion 28 and spaced leg members 29, the terminal ends of which are bent inwardly to form pivots 30. The pivots 30 are mounted in suitable apertures formed in the sides of the blocks. The pivots 30 are positioned slightly off center with respect to the point of mounting of the pins 26 so that under clamping action of the matrix holder a binding action will occur between the bight portions 28 and the pins 26, as will be described.

Attention is now invited to Figure 7 of the drawing wherein the matrix band is shown, and consists of a main body 31 of a width and length required for its application upon a given tooth. The body 31 is provided with terminal ends 32 and 33 of greatly reduced widths as clearly shown, the end 32 being formed as a continuation of the lower end of the body, while the end 33 is spaced slightly upward from said edge so as to align with a slot 34 at the opposite side of the body. It will be noted that the terminal ends are thus in a cross relationship, as shown in Figures 1 and 7. Each end 32 and 33 is provided with an aperture 35 for reception of respective pins 26 of the matrix. It is a known fact that a tooth is more or less "bell shaped" and of varying diameters and heights and for this reason the band is cut to fit each individual tooth, the bell-shape being provided for by cutting the band longitudinally at its base in an arcuate path. The band will thus fit snugly around a tooth when applied thereto.

In use, after a tooth has been prepared and is ready for filling, a matrix band is cut to fit the tooth and assembled as shown in Figure 7. Obviously, the matrix holder is placed in the mouth of the patient so that the squared end 22 may be engaged by the handle 23. We will say that the terminal end 32 of the band is to be attached to the movable block 17 and to the end 33 to the block 15. Each terminal end is passed beneath the respective bight portions 28 and respective pin of the blocks inserted in the apertures of the terminal ends. The band is now applied to the tooth and by affixing the handle 23 to the squared end and rotating the handle in a clockwise direction simultaneous movement of the blocks 15 and 17 in opposite directions will be effected, drawing upon the terminal ends and the band properly snugly around the tooth. As may be seen in Figures 3 and 8, movement of the blocks will tend to swing the loop devices 27 in the direction of the pins due to engagement between the bight portions 28 and inner portions of the terminal ends of the band. By reason of the divergence of the pins 26 and the off center pivoting of the loop devices 27 the band will be firmly held against slippage from the pins. Re-

verse rotation of the worm shaft 20 will lessen the tension of the matrix band for removal from the tooth.

While I have shown and specifically described the invention, this is by way of illustration only, and I consider as my own all such modifications as fairly fall within the scope of the appended claims.

I claim:

1. A means for securing respective ends of a crossed matrix band upon oppositely movable blocks comprising pins in the upper face of each block diverging from each other and adapted to receive a terminal end of a matrix band thereon and a loop device swingably mounted upon each block, the bight portion thereof overlying the band and cooperable with the pin for retaining the band thereon in one direction of movement of the blocks.
2. The structure of claim 1 in which the loop device is pivotally mounted off center with respect to the mounting of said pins.
3. In a dental matrix, the combination of a matrix band having reduced terminal ends, said band having an opening inwardly of the base of one of said ends adapted to receive the other end therethrough, each end having an aperture, a pair of oppositely movable block members, a pin member in the upper face of each block member adapted to be inserted in respective apertures of the terminal ends of the band, manual means for simultaneously moving the blocks, and a loop member on each block overlying respective terminal ends of the band and cooperative with respective pins for retention of the band to said block.
4. The structure of claim 3, in which the pin members diverge in opposite directions and said loop members are pivotally mounted off center from the mounting of the pin members.
5. A matrix band retainer comprising an elongated body member having a channel formed therein, said channel having opposed parallel flanges, a block member fixed at one end of the channel, a movable block slidably interengaged between said flanges and within the channel, each of the blocks having a threaded opening aligned with the longitudinal axis of the channel, the threads of the opening of one block being opposite to that of the opening of the other block, a worm shaft extended through the aligned openings and having threads complementary to respective openings, whereby to obtain reverse movements of the blocks upon rotation of the worm shaft, and each of said blocks having a pin arranged in divergent relation for engaging respective apertured ends of crossed terminals of a matrix band, and a loop member swingably mounted upon each block and overlying the terminal ends of the matrix band.

JAMES D. MORRISON.
